UNITED STATES PATENT OFFICE

1,968,298

CONTAINER CLOSURE

Benjamin F. Klein, Detroit, Mich.

Application November 22, 1932, Serial No. 643,904

2 Claims. (Cl. 221—60)

It is an object of the invention to provide a receptacle the upper margins of which also function as a closure to reinforce the closed extremity of a collapsible tube container, such as those commonly employed for holding shaving cream, toothpaste and the like, so that a very strong and durable joint results at the container base, and at the same time insuring permanent attachment of the receptacle to said container.

With this and other objects and advantages in view which will become apparent as the specification proceeds, the invention is hereinafter more fully described with the aid of the accompanying drawing, in which:

Figure 1 illustrates a front view of a collapsible tube container with the receptacle mounted thereon.

Figures 2 and 3 are sections on the lines 2—2 and 3—3 respectively of Figure 1, and

Figure 4 is a side view of Figure 1 partly in section.

Referring to the drawing, 1 designates a conventional collapsible tube container the lower end of which is flattened to form two walls 2 and 3 which lie contiguous to one another. The lower portions of the downwardly extending walls 2 and 3 are together upwardly folded as shown at 2a and 3a so that a space is left between the said walls and their upturned portions. The extremities 2b and 3b of the walls 2 and 3 are again downturned and are so folded that they lie between the walls 2 and 3 and the upwardly folded portions 2a and 3a.

The receptacle consists preferably of a single piece of material having a back 4, a base 5, a front 6 and a top 7. The latter extends rearwardly part way across the receptacle. From the inner or rear margin of the said top and upward projection 7a extends which is substantially parallel with an upward extension 4a of the back 4. Towards its upper end the extension 4a is forwardly and downwardly folded at 4b so that its extremity lies between one wall 2 and the downturned extremity 3b of the other wall of the tube container.

Formed integral with the back extension 4a are lateral tabs 4c which are forwardly and inwardly folded as shown in Figures 1 and 2 to hold the back extension 4a from spreading from the upward projection 7a and to hold all the wall portions 2, 2a, 2b, 3, 3a and 3b between them.

Intermediately of the height of the back 4 and front 6 are other lateral projections which are flexed towards one another to form side closures 4d and 6d. The latter are preferably so positioned that the vertical margins of the adjacent pairs rest substantially contiguous to one another but are so shaped that when inward pressure is exerted on them they flex apart sufficiently to permit ready insertion of a blade between

them. The height of these closures is preferably such as to prevent a blade from accidentally falling out of the receptacle, but is sufficiently less than the total height of the receptacle to permit the thicker portion of a blade having a reinforced margin to pass between the top 7 or base 5 and the adjacent extremities of the closures.

Across the back extension 4a an inward groove or corrugation 14 is usually formed which bears against the bottom of the tube wall 3 and prevents upward movement of the receptacle on the tube container.

When the upward projection 7a, extension 4a and its tabs 4c are in position relative to the tube walls 2 and 3 pressure is applied in any conventional manner to force them all into intimate contact after which it will be found that not only has a very strong tube closure been provided but also that the tube container and receptacle are securely connected together.

While in the foregoing the preferred embodiment of the invention has been described and shown it is understood that the construction is susceptible to such alterations and modifications as fall within the scope of the appended claims.

What I claim is:

1. A tube container closure comprising a collapsible tube container the lower portions of the walls of which are flattened and lie contiguous to one another, said walls being upwardly folded adjacent their flattened ends, in combination with a member resting against the outer upwardly folded wall portion and having one extremity downturned between the upwardly folded wall portions and the lower portion of the container body, and laterally disposed tabs on opposite sides of the said member extremity which are folded around the flattened margins of the upwardly folded container walls.

2. A tube container closure comprising a collapsible tube container the lower portions of the walls of which are flattened and lie contiguous to one another, said walls being upwardly folded adjacent their ends and having their extremities downturned between the upwardly folded portions and the lower end of the container, in combination with a member resting against the outer upwardly folded wall and having one extremity downturned between the container and the adjacent downturned wall extremity, and lateral tabs on said member extremity folded around the downwardly and upwardly folded container wall margins.

BENJAMIN F. KLEIN.
